G. WARMACK

GAS BURNER

Filed March 19, 1927

Patented Jan. 17, 1928.

1,656,549

UNITED STATES PATENT OFFICE.

GEORGE WARMACK, OF FORT SMITH, ARKANSAS.

GAS BURNER.

Application filed March 19, 1927. Serial No. 176,804.

This invention relates to gas burners and it is an object of the invention to provide a device of this kind comprising a tube provided with means to assure a flame effectively spreading over a desired heating surface with substantially no noise.

It is also an object of the invention to provide a burner of this kind comprising burner tubes together with means for effectively mounting the same in applied or working position.

The invention consists in the details of construction and in the combination and arrangement of the several parts of my improved gas burner whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:—

Figure 1 is a view partly in side elevation and partly in section illustrating a burner constructed in accordance with an embodiment of my invention;

Figure 2 is a sectional view taken substantially on the line 2—2 of Figure 1;

Figure 3 is a sectional view taken substantially on the line 3—3 of Figure 1;

Figure 4 is a fragmentary view in top plan illustrating in detail the upper or flame end of a tube in initial position when being applied;

Figure 5 is a view similar to Figure 4 with the tube in applied position;

Figure 6 is a fragmentary view in top plan of the burner tube support;

Figure 7 is a sectional view taken through a burner support constructed in accordance with a further embodiment of my invention;

Figure 8 is a fragmentary elevational view illustrating a slightly modified form of burner tube.

As disclosed in the accompanying drawing, 1 denotes a gas manifold having its extremities operatively engaged with the T joints 2. The assembled manifold 1 and joints 2 are of a length to bridge the space between the opposed walls 3 of a stove in which the burner is applied.

Coacting with one of the walls 3 and the

adjacent T joint 2 is a gas cock 4 controlling the admission of gas to the manifold 1 while the second wall 3 and adjacent joint 2 have associated therewith a closing plug 5. The cock 4 and plug 5 provide means whereby the manifold 1 is effectively supported by the walls 3.

The stem branches 2' of the joints 2 are upwardly and vertically disposed and in threaded engagement with each of said stem branches 2' is the lower end portion of an upstanding post or pin 6 which provides a supporting means for the burner tube support or brace B. The brace B is of a length to substantially bridge the space between the walls 3 and includes a bottom plate 7 which rests upon the upper ends of the branches 2', said plate 7 adjacent to each end being provided with an opening 8 through which a post or pin 6 is directed. One marginal portion of the plate 7 is defined by a vertically disposed plate 9 having its upper marginal portion continued by a plate 10 overlying the plate 7. This plate 10 has an opening 7' through which the post or pin 6 is also directed. Threaded through the plate 9 and engaging the pin or post 6 is a holding screw 11 providing means whereby the burner support B is effectively maintained in applied position upon each of the pins or posts 6. This bolt or screw 11 also permits the burner support B to be held in desired adjusted position at points lengthwise of a pin or post 6 as the requirements of practice may prefer.

The upper portion of the wall of the manifold 1 is provided therealong with spaced outlet openings 12 each of which being arranged directly below a burner tube T operatively supported by the support B. Each of the tubes T has its upper portion flat, as at 14, to project slightly beyond opposite sides of the tube and to provide a tit to produce a wide thin blue flame which will effectively spread over the desired heating surface, such as a radiant or asbestos back, thus assuring a maximum of heat.

Each of the tubes T is insertible through the vertically aligned openings 15 in the plates 7 and 10, each of said openings being provided with diametrically opposed notches or recesses 16 to permit the ready insertion through the plates 7 and 10 of the tit end portion of the tube T. After the tube T has been disposed through said plates 7 and 10, the tube is given an approximate quarter turn, as illustrated in Figure 5, whereby the

tube is effectively maintained in applied or working position. This quarter turning of the tube serves to bring in close contact from below with the plate 7 the outstanding annular bead or flange 17 carried by the lower portion of the tube T, thus further assuring an effective maintenance of the tube T in applied position with respect to the support B.

10 When the burner is applied within a stove, the plate 9 of the burner support B is preferably forwardly disposed and to further strengthen said support B, the inner marginal portions of the plates 7 and 10 have 15 lock seamed thereto or otherwise connected a brace plate 18. However, if the plates 7, 9 and 10 are sufficiently heavy this plate 18 may be dispensed with.

When the plate 9 is of relatively light material it is of advantage to dispose over the inner face of said plate 9 a reinforcing plate 19 through which each of the bolts or screws 11 is directed.

In the embodiment of the burner support 20 B' illustrated in Figure 7, said support comprises two sections having plates 9' in overlying relation and held in desired assembly through the medium of the bolts 20 or the like.

25 In Figure 8 I illustrate an embodiment of a tube T' wherein a separable flattened tip 14' is operatively engaged with the upper portion of the tube T'.

Interposed between the walls 3 and secured thereto, as at 21, is a brace member or strip 22 and the flattened portion 14 of each of the tubes T is received with an opening 23 in such member or strip 22. This member or strip 22 in addition to providing further support for the tubes T also serves to hold the same against turning movement, thus assuring the flame jets being maintained in desired positions.

From the foregoing description it is 45 thought to be obvious that a gas burner constructed in accordance with my invention is particularly well adapted for use by reason of the convenience and facility with which it may be assembled and operated,

and it will also be obvious that my invention 50 is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A gas burner construction including a 60 manifold, a burner support carried thereby, said burner support including spaced plates having aligned openings, each of said plates having recesses in communication with the openings, and a burner tube insertible through the openings in said plates, an end portion of the tube being flattened and extending beyond the support, said recesses permitting the extended portion of the tube to pass through the plates, said extended portion upon turning movement of the tube serving to maintain the tube in applied position with respect to the support, said manifold having an opening discharging into the tube. 70

2. A gas burner construction including a 75 manifold, a burner support carried thereby, said burner support including spaced plates having aligned openings, each of said plates having recesses in communication with the openings, and a burner tube insertible through the openings in said plates, an end portion of the tube being flattened and extending beyond the support, said recesses permitting the extended portion of the tube to pass through the plates, said extended portion upon turning movement of the tube serving to maintain the tube in applied position with respect to the support, said manifold having an opening discharging into the tube, 80 said tube adjacent to its opposite end being provided with an outstanding bead having close contact with a plate of the support upon such turning movement of the tube. 85

In testimony whereof I hereunto affix my signature.

GEORGE WARMACK.
